UNITED STATES PATENT OFFICE

ROLAND CHILTON, OF RIDGEWOOD, NEW JERSEY, ASSIGNOR TO ECLIPSE AVIATION CORPORATION, OF EAST ORANGE, NEW JERSEY, A CORPORATION OF NEW JERSEY

ENGINE STARTING MECHANISM

Application filed October 18, 1929. Serial No. 400,704.

This invention relates to engine starting apparatus of the type embodying inertia mechanism for cranking an engine.

It has been proposed heretofore to provide inertia starting mechanism for internal combustion engines, wherein the inertia element is constituted by the rapidly rotating element, for example the armature, of an electric motor. Such apparatus may be adapted for either manual or electrical actuation, and in order to prevent loss of power due to brush friction on the commutator of the motor, it is desirable to maintain the brushes out of engagement with the commutator when the engine is being cranked, or when the inertia element is being accelerated manually.

One of the objects of the present invention is to provide inertia starting mechanism of the type wherein the inertia element is constituted by the rotor of an electric motor, the mechanism embodying novel means whereby the brushes are normally maintained out of engagement with the commutator of the motor and are engaged therewith only when the inertia element is being accelerated electrically, said novel means including common control means for the brush engaging mechanism and the mechanism which drivably connects said inertia element with the manual accelerating means.

A further object is to provide novel starting apparatus of the above character which is adapted for manual or electrical actuation, or both, and which occupies minimum space and has minimum weight for its size.

One embodiment of the invention is illustrated in the accompanying drawings, but it is to be expressly understood that said drawings are for purposes of illustration only and are not to be construed as a definition of the limits of the invention, reference being had to the appended claims for this purpose.

45 In said drawings:

Fig. 1 is an elevation, partly in section, of one embodiment of the invention;

Fig. 2 is an end view of Fig. 1; and

50 Fig. 3 is a detail in perspective showing the brush mounting and actuating means.

Referring now to the drawings, wherein like numerals indicate like parts throughout the several views, the starting mechanism is housed in a sectional casing 4 of any suitable type, which casing is adapted to be secured by means such as bolts 5 to the casing of an internal combustion engine (not shown). Mounted in suitable bearings in the casing 4 is the shaft 6 of an electric motor, said shaft being provided with suitable teeth 7 meshing with a large gear 8 that is drivably connected through a suitable train of reduction gearing (not shown) with a clutch jaw 9. Preferably, a yielding driving connection is interposed between the gear 8 and the clutch jaw 9, said yielding connection in the form shown comprising friction clutch means 10 of the type described in my Patent No. 1,632,539, dated June 14, 1927.

70 The clutch jaw 9 is adapted to be shifted axially into engagement with a member of the engine to be started by any suitable shifting mechanism (not shown) actuated by a rock shaft 11. The mechanism above described is well understood in the art and constitutes no part per se of the present invention, and any known type of such mechanism can be employed which is suitable for the purpose described.

75 The electric motor for rotating the shaft 6 can be of any suitable type and in the form shown comprises a stationary field structure including pole pieces 12 having field coils 13 thereon and secured to the casing 4 in any suitable manner, as by means of screws or bolts 14. The rotating motor armature is constituted by a supporting plate 15 which is keyed at 16 to the shaft 6 and carries adjacent its periphery suitable laminations 17 and armature windings 18. The rotating armature thus constituted is of considerable weight and of relatively great radius and may constitute the inertia element of the starting mechanism, the energy of rotation of which is effective to rotate the clutch jaw 9 to crank the engine. The shaft 6 likewise carries a commutator 19 comprising a plurality of segments to which the armature windings 18 are suitably connect- 100

ed, and suitable brushes 20 are adapted to engage said commutator to operate the motor.

Means are provided for mounting the brushes 20 with respect to commutator 19, whereby said brushes are resiliently maintained out of engagement with said commutator under normal conditions and may be displaced into engagement with said commutator to rotate the motor armature or inertia element. In the form shown, the commutator 19 is housed in a cup 21 that is suitably secured to the casing 4 by means of a screw or screws 22, and a ring 23 is adjustably mounted on said cup, said ring having inner and outer flanges 24 as seen in Fig. 3. The upper part of the inner flange 24 is provided with a slot 25 through which one of the screws 22 extends, whereby the ring 23 is held fixed with respect to the cup 21 and the outer housing 4. Resilient arms 26, such as leaf springs, are mounted on pins 27 that extend between the inner and outer flanges 24 and each of said arms 26 carries a brush 20, the normal position of said brushes being out of contact with the commutator 19 as clearly shown in Fig. 2. The brushes 20 extend through registering openings 28 in the ring 23 and cup 21, and flexible leads 29 connect the brushes 20 with a terminal block 30.

As stated above, the starting mechanism is adapted to be actuated either manually or by power. Accordingly, suitable means are provided for flexing or bending the resilient arms 26 to depress the brushes 20 into engagement with the commutator 19, said brushes constituting a switch for energizing the motor when it is desired to actuate the starter by power. In the form shown, the outer flange 24 on the ring 23 is provided with an upwardly and laterally extending portion 31 which serves as a bracket on which a bell crank lever is pivoted by means of a pivot pin 32. The horizontally extending arm 33 of the bell crank lever has an eye 34 through which loosely extends a pin 35 carrying a block of insulating material 36 that is provided with portions 37 adapted to engage and flex the resilient arms 26. The vertically extending arm 38 of the bell crank lever is connected to a link 39 which passes freely through an opening in a lug 40 formed on a swinging lever 41 that is pivoted by means of a pin 42 on the starter housing 4. Resilient means such as a coil spring 43 is interposed between the lug 40 and a plate 44 secured to the link 39. An operating or control rod 45 is connected to the upper end of the lever 41, so that when the control rod is pushed to the right, as seen in Figs. 2 and 3, the lever 41 swings about its pivot and compresses the spring 43 thereupon by resiliently urging link 39 to the right

and rotating the bell crank lever on its pivot 32 to depress the arms 26 and brushes 20.

Preferably, the control rod 45 likewise serves to shift the clutch jaw 9 into engagement with the engine to be cranked after the inertia element has been accelerated either manually or by power. Accordingly the lever 41 is provided with a lug 46 which, when the control rod is pulled to the left as seen in Figs. 2 and 3, engages and rotates a swinging frame 47 that is preferably pivoted on the pin 42. An arm 48 on the frame 47 is connected by means of a link 49 and a rock arm 50 with the rock shaft 11 which, as above described, shifts the clutch jaw 9 axially into cranking position.

In the preferred embodiment of the invention, as illustrated, the common means for controlling the movement of the brush carrying arms 26 and the driving connection to the inertia element from the manual accelerating shaft 51 (Fig. 2) takes the form of a ratchet jaw 52 provided on the shaft 51, and adapted to engage a corresponding ratchet jaw 53 to drivably connect the cranking shaft 51 with an extension 54 thereof, said ratchet jaws being normally maintained in engagement by means of a pair of springs 55 suitably mounted as by means of screws 56 on the swinging frame 47.

The operation of the apparatus is as follows. The parts being in their normal position shown in the drawings, when it is desired to accelerate the starter manually, it is only necessary to rotate the cranking shaft 51 which transmits its rotation through the ratchet jaws 52, 53 and the shaft 51 to the starter gearing and rotates the inertia element constituted by the motor armature. As soon as the latter has been brought up to high speed and sufficient energy has been stored therein to start the engine, the operating rod 45 is pulled to the left as seen in Figs. 2 and 3 whereby the lever 41 is rotated and the lug 46 thereon engages the swinging frame 47 and rotates the rock shaft 11 through arm 48, link 49 and rock arm 50, whereupon as above described the clutch jaw 9 is shifted axially into cranking engagement with the engine to be started. As soon as the engine starts, the engine crank shaft will overrun the clutch jaw 9 and the inclined faces of the jaw teeth will be effective to displace the jaw 9 axially to the position shown in Fig. 1. Since the lever 41 has been rotated in only one direction, namely, counter-clockwise as seen in Fig. 2, the link 39 has not been shifted and the brushes 20 remain out of engagement with the commutator 19 so that there is no brush load to be overcome in accelerating the inertia element or in cranking the engine.

If it is desired to accelerate the starter by power, the operating rod 45 is first pushed to the right as seen in Figs. 2 and 3 whereupon

the brushes 20 are depressed as above described into engagement with the commutator 19. The motor then starts and as soon as the desired speed of rotation of the armature has been reached, the control rod 45 is pulled sharply to the left to shift the clutch jaw 9 as above described into cranking position, whereupon the spring 43 is released and the resilient arms 26 lift the brushes out of engagement with the commutator, thereby simultaneously breaking the motor circuit and removing the brush load from the commutator. When this leftward movement occurs the resilient arms 55 swing in a counter-clockwise direction, thus permitting the clutch element 52 to move away from the associated clutch element 53. This disengagement of the clutch 52-53 protects the operator, since it eliminates the possibility of a sudden reversal of the crank handle 54 in the event of a backfire of the engine.

Since the brushes are always out of engagement with the commutator when the engine is being cranked, none of the power stored in the inertia element is lost in overcoming the brush load. Moreover manual cranking of the starter is greatly facilitated by the removal of the brush load, and at the same time the brushes may be readily moved into engagement with the commutator whenever it is desired to use the electric motor. The apparatus, while simple and economical to construct, is effective and reliable in operation and is designed so as to have the least possible weight and to occupy the least possible space. The brushes and the resilient mounting therefor are bodily adjustable around the commutator axis without disturbing or interfering with the means whereby the brushes are depressed into engagement with the commutator.

While only one embodiment of the invention has been described and illustrated in the drawings, it is to be expressly understood that the invention is not limited thereto, but is capable of embodiments other than that described. For example, the invention is not limited to the particular type of electric motor shown, since any other suitable type of electric motor may be used, the rotor of which constitutes the inertia member. Moreover, while the brushes serve as a switch to close the motor circuit, it will be understood that an additional switch may be employed if desired. Likewise changes may be made in the form, construction and arrangement of the parts without departing from the spirit of the invention, and reference is therefore to be had to the appended claims for a definition of the limits of the invention. For claims to the electric motor and parts thereof, per se, reference is to be had to my divisional application Serial No. 647,673, filed Dec. 16, 1932.

What is claimed is:

1. In engine starting apparatus, the combination of a driven member adapted to engage and crank an engine to be started, inertia mechanism drivably connected with said driven member and including an electric motor having an armature and commutator, brushes for said commutator, arms carrying said brushes normally out of engagement with said commutator, manually operable means for accelerating said inertia mechanism comprising a hand-cranking shaft and a clutch mechanism interposed between said cranking shaft and inertia mechanism, and common means for controlling said clutch and said brush carrying arms. 70

2. In engine starting apparatus, the combination of a clutch member adapted to engage and crank an engine to be started, inertia mechanism drivably connected with said clutch member, said mechanism including an electric motor having an armature and a commutator, a brush for said commutator, a resilient arm supported at one end and carrying said brush normally out of engagement with said commutator, manually operable means for accelerating said inertia mechanism comprising a hand-cranking shaft and a clutch mechanism interposed between said cranking shaft and inertia mechanism, and common means for controlling said second clutch and said brush carrying arms. 85

3. In engine starting apparatus, the combination of a driven member adapted to be moved into cranking engagement with an engine to be started, inertia driving means drivably connected with said driven member and including an electric motor, said motor having a rotating armature and a commutator, brushes for said commutator, a plurality of resilient arms each carrying one of said brushes normally out of engagement with said commutator, manually operable means for accelerating said inertia mechanism comprising a hand-cranking shaft and a clutch mechanism interposed between said cranking shaft and inertia mechanism, and common means for controlling said clutch and said brush carrying arms. 100

4. In apparatus of the character described, the combination of a clutch member adapted to be shifted to engage and crank an engine to be started, inertia driving means operatively connected with said clutch member and including an electric motor, a second clutch manually rotatable to accelerate said electric motor, said motor having an armature and a commutator, brushes for said commutator, resilient arms carrying said brushes normally out of engagement with said commutator, common means for controlling said second clutch and said brush carrying arms. 110

120

125

130

5. Engine starting mechanism comprising a clutch member adapted to engage and crank an engine, inertia driving mechanism therefor, said mechanism including an electric motor having an armature and a commutator, brushes for said commutator, a housing for said commutator having openings therein, resilient brush carrying means mounted exteriorly of said housing, said 10 brushes extending through said openings and normally being out of engagement with said commutator, manually operable means for accelerating said inertia mechanism comprising a hand-cranking shaft and a 15 clutch mechanism interposed between said cranking shaft and inertia mechanism, and common control means for said second clutch and brush carrying arms.

6. Engine starting mechanism comprising 20 a member adapted to engage and crank an engine to be started, inertia driving mechanism therefor, said driving mechanism including an electric motor having an armature and commutator, brushes for said commutator, a housing for said commutator having openings therein, a member carried on said housing and adjustable thereon around the axis of said commutator, resilient brush carrying means mounted on said 25 member, said brushes extending through said openings and normally being out of engagement with said commutator, manually operable means for accelerating said inertia mechanism comprising a hand-cranking shaft and a clutch mechanism interposed between said cranking shaft and inertia mechanism, and common control means for said clutch and brush carrying arms.

7. Engine starting mechanism comprising 30 a member adapted to engage and crank an engine to be started, inertia driving means therefor, said means including an electric motor having a rotating armature and a commutator, brushes for said commutator, a housing for said commutator, a supporting member mounted on said housing, said housing and supporting member having registering openings, resilient brush carrying 35 arms mounted on said supporting member, said brushes extending through said openings and normally being out of engagement with said commutator, manually operable means for accelerating said inertia mechanism comprising a hand-cranking shaft and a clutch mechanism interposed between said cranking shaft and inertia mechanism, and common control means for said clutch and brush carrying arms.

8. In engine starting apparatus, the combination of a member adapted to be shifted to engine cranking position, inertia mechanism drivably connected with said member and including an electric motor having 40 an armature and a commutator, brushes for

said commutator, a housing for said commutator, a supporting member mounted on said housing, said supporting member and housing having registering openings, a plurality of resilient brush carrying arms mounted on said supporting member, said brushes extending through said openings and normally being out of engagement with said commutator, manually operable means for accelerating said inertia mechanism comprising a hand-cranking shaft and a clutch mechanism interposed between said cranking shaft and inertia mechanism and common means for controlling said clutch and said brush carrying arms.

9. In engine starting mechanism, the combination of a clutch member adapted to be shifted to engine cranking position, inertia mechanism drivably connected to said clutch member and including an electric motor having an armature and commutator, brushes for said commutator, a plurality of resilient arms carrying said brushes normally out of engagement with said commutator, manually operable means for accelerating said inertia mechanism comprising a hand-cranking shaft and a clutch mechanism interposed between said cranking shaft and inertia mechanism and common means for controlling said second clutch and said brush carrying arms.

10. In engine starting mechanism, the combination of a clutch member adapted to be shifted to engine cranking position, inertia mechanism drivably connected to said clutch member and including an electric motor having an armature and commutator, a supporting member surrounding said commutator, brushes resiliently mounted on said member and normally being out of engagement with said commutator, means mounted on said member for holding said brushes in engagement with said commutator, said member brushes and holding means being bodily adjustable as a unit around the axis of said commutator, manually operable means for accelerating said inertia mechanism comprising a hand-cranking shaft and a clutch mechanism interposed between said cranking shaft and inertia mechanism, and common control means for said second clutch and brush carrying arms and means for actuating said holding means.

11. In engine starting apparatus, the combination of a driven member adapted to be shifted to engage and crank a member of an engine to be started, an electric motor including a stationary and a rotating element, the latter constituting an inertia member drivably connected with said driven member, a commutator and brushes for said motor, a support, brush-carrying arms mounted on said support, manually operable means for accelerating said inertia mechanism comprising a hand-cranking shaft

and a clutch mechanism interposed between said cranking shaft and inertia mechanism, said brushes being normally out of engagement with said commutator, and common 5 means for controlling said clutch and said brush carrying arms.

12. In engine starting apparatus; the combination of a clutch member adapted to engage and crank an engine to be started, 10 an electric motor having a rotor that constitutes an inertia element and is drivably connected with said clutch member, a commutator for said motor, a supporting member rotatably mounted about the commuta- 15 tor axis, a plurality of arms mounted on said supporting member, brushes carried by said arms and normally out of engagement with said commutator, manually operable means for accelerating said inertia mechanism comprising a hand-cranking shaft and a clutch mechanism interposed between said cranking shaft and inertia mechanism, and common 20 means for controlling said second clutch and said brush carrying arms.

25 In testimony whereof I have signed this specification.

ROLAND CHILTON.
